(57) **CLAIM**

The ornamental design for a vessel location assistance device, as shown and described.

DESCRIPTION

FIG. 1 is a top perspective view of a vessel location assistance device in accordance with a first embodiment of the invention;

FIG. 2 is a front view of the vessel location assistance device of FIG. 1;

FIG. 3 is rear view of the vessel location assistance device of FIG. 1;

FIG. 4 is a right side view of the vessel location assistance device of FIG. 1;

FIG. 5 is a left side view of the vessel location assistance device of FIG. 1;

FIG. 6 is a top view of the vessel location assistance device of FIG. 1;

FIG. 7 is a bottom view of the vessel location assistance device of FIG. 1;

FIG. 8 is a top perspective view of a vessel location assistance device in accordance with a second embodiment of the invention;

FIG. 9 is a front view of the vessel location assistance device of FIG. 8;

FIG. 10 is rear view of the vessel location assistance device of FIG. 8;

FIG. 11 is a right side view of the vessel location assistance device of FIG. 8;

FIG. 12 is a left side view of the vessel location assistance device of FIG. 8;

FIG. 13 is a top view of the vessel location assistance device of FIG. 8; and,

FIG. 14 is a bottom view of the vessel location assistance device of FIG. 8.

The broken lines shown in the various figures are depicted for illustrative purposes only and form no part of the claimed design.
